UNITED STATES PATENT OFFICE.

DAVID ADDISON LANE, OF AUSTIN, TEXAS.

SHADE-ROLLER.

1,171,215.

Specification of Letters Patent. Pater

Application filed February 4, 1915. Serial No. 6,047.

To all whom it may concern:

Be it known that I, DAVID A. LANE, a citizen of the United States, residing at Austin, in the county of Travis and State of Texas, have invented certain new and useful Improvements in Shade-Rollers, of which the following is a specification.

This invention relates to an improvement in window shades and more particularly to an improvement in shade rollers and brackets.

It is well known that window shades are generally very insecurely fastened to their rollers, and that often times by pulling a shade full length it is ripped or torn from the roller, thus necessitating either the purchase of a new shade and roller or the expenditure of much time and labor in repairing the torn shade and securing it to its roller.

It is the principal object of this invention to obviate the above mentioned objections by providing means whereby downward pull of the shade will be stopped while yet a turn or two of the shade remains on the roller, so as to prevent accidental ripping or tearing of the shade from its roller.

Another object of the invention is to provide an improved device of the class described incorporating a spring actuated detent or pawl normally tending to move into a recess provided in the roller for limiting or stopping the rotary movement of the latter, the pawl being normally maintained out of engagement with the recess by the action of the curtain in covering the recess as the curtain rolls upon its roller, the curtain however being provided with a cut-away portion adapted when there are only a few remaining turns on the roller, to uncover the recess whereby to allow the detent to fall or drop into the same for stopping the movement of the roller.

Still another object is to provide an improved device of the class described which will be extremely simple durable efficient in operation and inexpensive to manufacture.

With these and other objects in view which will become apparent as the description proceeds, the invention resides in the construction, combination and arrangement of parts, hereinafter more fully described and claimed, and illustrated in the accompanying drawing, in which like characters

of reference indicate the several figures, of which

Figure 1 represents a view in section taken vertically on a plane indicated in Fig. 1 looking in the direction of the arrow. Fig. 2 is similar to Fig. 1 showing a view in perspective of the mechanism shown in Fig. 1, said being in disassembled position. Fig. 3 represents a view in perspective of the elements of the mechanism shown in Fig. 4, and Fig. 5 represents a view in perspective similar to Fig. 3 showing the assembled form of bracket and roller.

In carrying out my invention a roller indicated generally at 6 is secured in the usual manner. The roller is supported on a window shade 8 of brackets, in the usual manner, the brackets being indicated generally at 7. The mechanism by which the roller is controlled is of ordinary construction, the shade being lowered in the ordinary and well known manner.

A roller at one end is provided transversely with a recess at 10 terminating at one end 11 and at its opposite end 12 at the periphery of the roller. The roller is a metallic cap or sleeve 12 provided with a shoulder 13 forming a lining at the end of the recess.

Pivotedly connected to the roller is a pawl 14 preferably in the form of a metal having its end 15 into engagement with the recess 10. The pawl is angular shaped piece of metal having its end 15 into engagement with the recess 10.

The shade 6 at one end 12 is provided with a shoulder 13, the width of the shoulder 13 being substantially equal to the width of the metal sleeve 12.

of the cut-away portion is such that when the shade is being unrolled, one or two turns of the shade remain upon the roller at the time the recess in the roller is uncovered 5 by the shade. It will of course be understood that as the shade is rolled up the turns of the shade beyond the recessed portion thereof overhang and house the recess 9 in the roller. Now the arrangement of 10 the pawl is such that it lies above the roller and may be actuated either by gravity or by a spring. It normally bears against the shade when the latter is wound, in such position that when the recessed portion of 15 the shade uncovers the recess in the roller, the pawl will drop into the recess and will be engaged by the shoulder 11 thereof in the manner indicated in Fig. 3 for stopping the rotary movement of the roller and hence 20 terminating the downward movement of the shade while yet there is a turn or two of the shade left upon the roller so that said shade cannot be pulled out to its full extent and ripped or torn apart or away 25 from the roller.

In the arrangement shown in Figs. 1-4 inclusive the means for mounting the pawl consists of a bar 17 formed integrally with brackets 7 and bent at right angles thereto 30 into engagement with an ear 18 formed integrally with and bent at right angles to the back 19 of the bracket. The bar 17 is disposed horizontally and upon it the rear end 20 of the pawl is loosely turned, in 35 such manner that the pawl may rock upon said bar. The pawl may be either spring or gravity actuated, and in the former case a length of spring material indicated at 20 is turned upon bar 17, and at one end 40 extends through a recess 21 in the upper edge of back 19 of the bracket into engagement with the casing 8. The opposite end of the spring extends in the opposite direction and is projected upwardly through a 45 slot indicated at 22 in the pawl and bears against the upper face of the latter whereby said pawl may be maintained in engagement with the roller.

In the form indicated in Figs. 5 and 6 50 the bracket 7^a is of the ordinary common type. Against the back 19^a of this bracket is adapted to be secured a plate 23 having a right angular bent end 24 on which is integrally formed the bar 17^a which bears 55 at one end against an ear 18^a also formed on plate 23. On the bar 17^a the pawl 14^a is pivoted in the usual manner. In Figs. 5 and 6 also this pawl is adapted to be actuated by gravity or by operation of the 60 spring indicated at 21^a, similar in arrangement and operation to spring 21.

In both structures shown in the drawing the pawl is in such position that when the recess in the roller is uncovered by 65 drawing the shade from the roller the pawl

will drop into the recess to be engaged against its shoulder for stopping the withdrawal of the shade. Upon jerking the shade and releasing it in the ordinary manner the roller will be actuated in a reversed direction so as to roll the shade upon it, and as it moves in the reverse direction the pawl will ride over the floor of the recess onto the periphery of the roller and over the turns of the shade as the latter 75 becomes wound on the roller. The free passage of the shade up and down is not interfered with in the least by the action of the pawl in limiting the movement of the shade. 80

The recess 9 is arranged at such point in the periphery of the roller, that shoulder 11 will come in contact with the pawl just before the ratchet mechanism, which is contained within the roller, and which is of the ordinary usual construction, takes up another notch or clicks into locking position for maintaining the shade at adjusted height, so that sufficient play is allowed whereov the curtain mat 30 moved up and 90 down to admit of the release of the latch in the ratchet mechanism so as to allow starting of upward movement of the shade.

Although I have described the preferred embodiment of my invention, I may desire 95 to make such changes in the construction, combination and arrangement of parts thereof as do not depart from the spirit of the invention and the scope of the appended claims. 100

I claim:—

1. In a device of the class described, the combination of a roller having a transverse recess provided therein and adapted to form a shoulder at one end of the recess, a metallic sleeve disposed upon said roller and provided with a stamped portion engaging in said recess against the floor and shoulder thereof, a flexible shade secured to and adopted to be wound upon the roller and in position to overhang the recess, said shade being provided adjacent the roller with a cut-away portion whereby the recess may be uncovered as the shade is drawn from the roller, a bracket in which said roller is pivoted, and a pawl pivotally connected to the bracket and in such position as to drop into the recess when the latter becomes uncovered whereby to limit the movement of the shade, substantially as described. 110

2. In a device of the class described, the combination of a roller having a recess provided transversely near one end thereof for forming a shoulder, a bracket upon which said roller is journaled, a shade secured to 125 and adapted to be wound upon the roller and having a cut-away portion adjacent the roller whereby the shade may be unwound for uncovering the recess, and a pawl pivotally connected to the bracket and adapted 130

to engage within the recess upon uncovering of the latter whereby to stop the unwinding movement of the shade.

3. A device of the class described comprising a roller having a recess disposed transversely near one end thereof and providing an inclined floor and a shoulder at one end of the floor, a shade carried on the roller and adapted to be wound thereon whereby to cover said recess, said shade adjacent the roller being provided with a cut-away portion whereby the recess may be uncovered, a bracket in which said shade is journaled and a pawl carried by the bracket and adapted to engage within said recess against the shoulder for limiting the movement of the shade in one direction, said shade adapted when moved in the opposite direction to wind upon the roller and engage beneath said pawl for lifting the latter out of engagement with the recess.

4. A device of the class described comprising a roller having a transversely disposed recess formed near one end thereof, a shade secured to and adapted to be wound upon the roller and adapted to cover the recess

when the shade is in wound up position, said shade being provided with a cut-away portion adjacent the roller whereby the recess may be uncovered as the shade is unwound from the roller, and means engaging on the shade above the roller and adapted to drop within the recess when the latter is uncovered whereby to limit the unwinding movement of the shade.

5. In a device of the class described, the combination with a roller having a recess formed therein, and a shade secured to and adapted to be wound on the roller in such position as to cover the recess and provided with a cut-away portion whereby the recess may be revealed as the shade nears the downward terminal of its unwinding movement, of a pawl bearing upon the roller and adapted to engage within the recess for limiting the unwinding movement of the shade.
